DESIGN FOR A FOLDABLE MINIATURE CHRISTMAS CRIB

Alfred Ochs, New York, N. Y.

Application April 25, 1944, Serial No. 113,374

Term of patent 3½ years

(Cl. D29—23)

To all whom it may concern:

Be it known that I, Alfred Ochs, without nationality, residing at New York, in the county of New York and State of New York, have invented a new, original, and ornamental Design for a Foldable Miniature Christmas Crib, of which the following is a specification, reference being had to the accompanying drawing, forming part thereof.

Fig. 1 is a plan view of a foldable miniature Christmas crib in the unfolded position, embodying my new design

Fig. 2 is a front view of the crib folded and set-up in the folded position, and

Fig. 3 is a sectional view taken on line 3—3 of Fig. 2.

I claim:

The ornamental design for a foldable miniature Christmas crib, as shown.

ALFRED OCHS.
